US0D1099265S

(12) **United States Design Patent** (10) **Patent No.:** **US D1,099,265 S**
(45) **Date of Patent:** **** Oct. 21, 2025**

(54) **STATIC BALANCING VALVE**

(71) Applicant: **Watts Regulator Co.**, North Andover, MA (US)

(72) Inventors: **Sergio Fontana**, Rovereto (IT); **Paolo Moruzzi**, Villa Lagarina (IT); **Fabio Gunsch**, Riva del Garda (IT); **Alfredo Marco Cucciniello**, Milan (IT)

(73) Assignee: **Watts Regulator Co.**, North Andover, MA (US)

(**) Term: **15 Years**

(21) Appl. No.: **29/945,761**

(22) Filed: **Jun. 5, 2024**

(57) **CLAIM**

The ornamental design for a static balancing valve, as shown and described.

DESCRIPTION

FIG. 1 is a top perspective view of a static balancing valve.

FIG. 2 is a front view thereof.

FIG. 3 is a back view thereof.

FIG. 4 is a top view thereof.

FIG. 5 is a left side view thereof.

FIG. 6 is a right side view thereof; and,

FIG. 7 is a bottom view thereof.

The broken lines shown in the figures are for the purpose of illustrating portions of the static balancing valve and form no part of the claimed design.

1 Claim, 7 Drawing Sheets
